UNITED STATES PATENT OFFICE

DAVID ALLEN SHINN, OF LIVINGSTON, WISCONSIN

CHIMNEY-SWEEPING APPARATUS

Application filed March 20, 1928. Serial No. 263,131.

This invention relates to chimney sweeping apparatus.

An important object of the invention is the provision of apparatus for sweeping chimneys which will eliminate the necessity of climbing upon the roof of a building to install the same.

A further and more specific object of the invention is to provide a chimney sweeping apparatus having in combination therewith an extensible support which may be manipulated from the ground to place the sweeping apparatus in proper relation to the chimney for operation therein.

15 A further object of the invention is to produce a device which may be manipulated from the ground to cause reciprocation of the sweeping device in the chimney.

20 A still further object of the invention is to provide means for clearing the soot removed from the chimney which is likewise operable from the ground.

25 These and other objects I attain by the construction shown in the accompanying drawings, wherein for the purpose of illustration is shown a preferred embodiment of my invention and wherein:—

Figure 1 is a side elevation showing chimney sweeping apparatus constructed in accordance with my invention in use, parts being broken away;

Figure 2 is a front elevation thereof;

Figure 3 is an enlarged detail view through the brush mechanism;

35 Figure 4 is an enlarged detail sectional view through the soot pan;

Figure 5 is a section on the line 5—5 of Figure 2.

Referring now more particularly to the 40 drawings, the numerals 10 and 11 generally designate the sections of an extensible support similar to an extension ladder. The section 10 has guides 12 in which the section 11 is slidable and has at its upper end a pulley 13 over which is trained a rope 14, one end of which is secured to the lower end of the section 11 and the opposite end of which is extended to the ground, so that from the foot of this support, it may be extended as to 45 its effective length.

At its upper end, the section 11 has secured thereto a group of legs 15 which are parallel to one another and acutely arranged with relation to the section. These legs define a substantially rectangular opening and are provided at their lower ends with outwarded feet 16 adapted to rest upon the cap of a chimney C. Above the center of the opening defined by the legs 15, the side members of the section 11 are connected by transverse shafts or supports 17 mounting sheaves 18 and 19 over which are trained ropes or cables 20 and 21.

The rope 20 is secured to a brush block 22, the sides of which have connected thereto by 65 springs 23, brushes 24 for engaging the walls of the chimney.

This block may be formed of any suitable light material and is recessed in its under surface for the reception of a counterweight, 70 designated at 25. The block and counterweight are apertured for the passage of the flexible element 21, as indicated at 26. This flexible element beneath the block is attached to a soot pan 27 which has upwardly flaring side walls 28, the edges of which are provided with marginal extensions 29 of rubber or other suitable flexible material.

In use of the apparatus, the support is extended until the legs 15 may be positioned to engage the feet thereof with the cap of the chimney. The brush and soot pan are then lowered into the chimney, the soot pan being lowered to the lower end of the chimney and the brush being reciprocated therein until the cleaning operation is completed. The brush is then elevated with the pan and may be extended into the space between the legs 15 to insure ready disengagement of the device from the chimney. The brush and pan 90 may be stored within this space during transportation of the device from place to place.

It will be obvious that a device of this character will eliminate the necessity for many dangerous climbs in chimney sweeping and will provide an apparatus whereby the sweeping operation may be carried on expeditiously and efficiently. It will also be obvious that the construction hereinbefore set forth is capable of a certain range of 100

change and modification without materially departing from the spirit of the invention and I accordingly do not limit myself to such specific structure except as hereinafter claimed.

8 I claim:—

9 In a chimney sweeping apparatus, a ladder adapted to be arranged with its upper end extending across the upper end of the
10 chimney, legs extending downwardly from the upper end of the ladder and adapted to rest upon the upper end of the chimney to support the upper end of the ladder from the chimney, a sweep element provided with
15 a passage extending vertically therethrough, means suspending the sweep element from the upper end of the ladder for vertical movement in the chimney, a soot collector, and means connected to the soot collector
20 and passing through the passage in the sweep element and connected to the upper end of the ladder to suspend the soot collector for vertical movement in the chimney.

25 In testimony whereof I hereunto affix my signature.

DAVID ALLEN SHINN.
